Design for a Carpet Pattern.

The schedule referred to in these Letters Patent and making part of the same.

Be it known that Eleazar J. Key, of Lowell, in the County of Middlesex and State of Massachusetts, have originated and designed a new pattern for carpets or other fabrics, of which the following is a full, clear and exact description, reference being had to the accompanying drawings, making part of this specification.

A is a rosette resting on a block B, said block is surrounded by scroll work.

1. 1. 1. 1. 1. are halves of a rosette similar to A.

2. 2. 2. 2. 2. are halves of blocks similar to B, surrounded by scroll work like figure A and B.

The rest of the design is composed of branches and rosettes.

This specification refers to parts between the blue lines.

The colors employed for the different portions of the design, may be varied to suit the taste and wish of the manufacturer.

Claim.
